STEAM-TURBINE.

1,287,603.

Specification of Letters Patent. Patented Dec. 10, 1918.

Application filed June 24, 1915. Serial No. 36,034.

To all whom it may concern:

Be it known that I, EARLE R. NEWTON, a citizen of the United States, resident of Nyack, county of Rockland, State of New York, have invented a certain new and useful Improvement in Steam-Turbines, of which the following is a specification.

The objects I have in view are to improve the efficiency of turbines when run at reduced power and when run at full power, thereby producing a turbine which is efficient under both conditions of operation.

These and further objects will more fully appear from the following specification and accompanying drawings, considered together or separately.

In the drawings—

Figure 1 is a plan view of a twin screw turbine set embodying my invention;

Fig. 2 is a similar view of a modification, and

Fig. 3 is a detail view of a turbine comprising high and low pressure elements.

In the drawings I illustrate a steam turbine comprising a high pressure element and a low pressure element which exhaust into a condenser, as shown in Fig. 3 or into an additional turbine element which exhausts into a condenser, as shown in Figs. 1 and 2. I have illustrated the additional element in Figs. 1 and 2 as consisting of a low speed high pressure element and a low speed low pressure element; the latter of which exhausts into a condenser.

It is well understood that the blade speed of a turbine must bear a definite relation to the steam speed in order to secure the best efficiency. If a turbine is designed for high blade speeds there must be a considerable drop in pressure between stages or rows of blades, in order to get the steam velocity necessary to accommodate the high blade speed. Turbines designed for low blade speed will operate with steam of lower velocity, hence the drop in pressure between stages or rows of blades will be less. For this reason turbines having a high blade speed, to operate with efficiency, should be divided into few stages or rows of blades while on the other hand turbines having a low blade speed, to be efficient, should be divided into a greater number of stages or rows of blades. In turbines designed to give

good economy at reduced power (that is, with reduced steam flow and reduced revolutions) the stages after the first are very apt to be over-speeded when running at the normal full power and overload conditions; that is, the ratio

$$\frac{\text{blade speed}}{\text{steam speed}} \quad 60$$

becomes too great and the efficiency falls off. In other words there are too many stages or rows of blades in series for the full power condition of operation.

If, on the other hand, the turbines are designed to give the best possible efficiency at full power the efficiency at reduced power will be poor, because a turbine thus designed will have too few stages or rows of blades in series to give good efficiency at the reduced powers. That is, the ratio of

$$\frac{\text{blade speed}}{\text{steam speed}} \quad 75$$

for the various stages or rows is too small.

The practice in the past has been either to design the turbines for an intermediate power and sacrifice some efficiency at both the high powers and the low powers, or to by-pass the steam around certain stages at the high powers. These by-passed stages not only deliver no work to the shaft, but they absorb considerable power in rotation losses and in eddy current losses.

According to the present invention I design the turbine so that it is efficient at both reduced and full powers and I secure this effect by dividing the turbine into a comparatively large number of stages or rows of blades. For operating at reduced power I run the steam entirely through the turbine. At full power, steam flows through a portion of the turbine and is then divided, part being passed through one portion of the turbine, and part being passed through another portion of it. By this means the turbine in effect is composed of a large number of stages or rows of blades when operating at reduced power, hence with a small drop in pressure between stages or rows of blades and consequently low steam velocity to accommodate the low blade speeds. The turbine when run at full power in effect utilizes few stages or rows of blades for the

expansion of the steam so that a large pressure drop is secured at each stage or row of blades, and hence the necessary high velocity of the steam to effectively act upon the 5 blades moving at higher speeds is obtained.

The drawings illustrate several embodiments of the invention.

Referring to Fig. 3, a high pressure steam turbine element 1 and a low pressure steam 10 turbine element 2 are mounted upon shafts 3 and 4 respectively. Each element is provided with a plurality of stages or rows of blades. Each shaft is provided with a gear 5 and 6 and these two gears engage with a 15 larger gear 7. The gear 7 drives a shaft 8 which rotates a propeller 9. These gears permit the turbine to turn at a much higher rate of speed than the propeller. These 20 gears constitute one form of speed reduction mechanism. Other forms of speed reduction mechanism may be employed or the speed reduction mechanism may be omitted and the power be taken directly from the shafts 3 and 4. Steam is admitted to the element 25 1 through the inlet 10. From the outlet of the element 1 the steam exhausts. It may go direct to the condenser, or to an additional turbine (see Figs. 1 and 2) or it may traverse a passage 11 to the outlet of the element 2 and from thence directly to the condenser (see Fig. 3). A passage 12 connects the inlet end of the element 1 (preferably beyond the first stage or row of blades) and the inlet of the element 2. A third passage 30 13 connects the outlet of the element 1 to the inlet of the element 2. The condenser 14 is connected to the outlet of the element 2 by a passage 15. The passage 11 is provided with a valve 16. The passage 12 is provided 35 with a valve 17, and the passage 13 is provided with a valve 18. In running with reduced steam flow and reduced revolutions steam is admitted through the inlet 10, the valves 16 and 17 being closed and the valve 40 18 opened. The steam after traversing all of the stages or rows of blades of the element 1 will go through the passage 13 and will then traverse all of the stages or rows of blades of the element 2 and thence it will 45 enter the condenser. This produces in effect a long turbine formed of a large number of stages or rows of blades with a relatively low pressure drop between each. The velocity of the steam, therefore, will be in 50 proper proportion to the speed of the blades. For operating at full power the valves 16 and 17 will be opened and the valve 18 closed. The steam entering the passage 10 will flow through the first stage or rows of 55 blades and then divide and part flow through the element 1 and exhaust through the passage 11 to the condenser. The other part of the steam will pass through the passage 12 and thence through the element 2 to the 60 condenser. Steam will run therefore in part 65

through substantially all of the two elements. Each element can be designed to develop about equal power. The total drop in pressure of the steam from the inlet to the outlet of each element will be through 70 about half the number of stages as in the case when the steam passes in series through the two elements. The pressure drop in each stage, therefore, will be greater and the velocity of the steam will be greater. The velocity of the steam will therefore be more 75 nearly in accordance with the speed of the blades so that efficient action will be secured.

It is to be noted from an examination of Fig. 3 that the passage 12 is connected to the 80 element 1 beyond the first stage or rows of blades therein. This is an effective arrangement because the first stage or rows of blades ordinarily may be designed so that it will be efficient at reduced revolutions or at full 85 power. As also shown in Fig. 3, the passage 11 is provided with branches having valves 19 therein. These branches admit steam to stages in advance of the last stage of the element 2. By opening and closing certain of 90 the valves 19 and closing the valve 16, the steam from the outlet of the element 1 may be caused to enter certain of the stages of the element 2 in advance of the discharge end thereof, causing a back pressure within 95 the element 1, with a consequent reduction in the velocity in steam in such element. This arrangement may be utilized when it is desired to secure a different distribution of energy between the two shafts. 100

Referring to Fig. 2, the arrangement substantially as hereinbefore described is applied to a twin screw turbine arrangement. In this arrangement a high pressure low speed turbine element 20 is connected to a 105 shaft 21 which drives a propeller 22. The steam discharges from the elements 1 and 2 through a passage 23 to the element 20. A low pressure low speed turbine element 25 is connected to the shaft 8 and the outlet of 110 steam from the element 20 is admitted to the inlet of the element 25 through a passage 26. 115

Fig. 1 represents an embodiment of the invention in which the steam passage 11 from the element 1 connects to the inlet end of the element 20 while the passage 15 from the low pressure high speed element 2 connects to an intermediate stage of the element 20. By this arrangement when operating 120 under full power the steam will be discharged from the element 1 directly into the head of the element 20, while the steam discharging from the element 2 will enter the element 20 beyond the head thereof. 125

In both the structures illustrated in Figs. 1 and 2, a valve 24 is arranged in the passage 15.

It is apparent that an arrangement may be employed as shown in Figs. 1 and 2 but 130

utilizing the elements 1, 2 and 25 only, the steam being admitted directly from the elements 1 and 2 to the element 25.

It is also apparent that a twin screw arrangement may be used omitting the element 25. It is also apparent that the arrangement shown in Fig. 3 may be used, but with the elements 1 and 2 being mounted upon a single shaft.

10 In accordance with the provisions of the patent statutes, I have described the principle of my invention, together with the apparatus which I now consider to represent the best embodiment thereof; but I desire 15 to have it understood that the apparatus shown is merely illustrative and that the invention may be carried out in other ways.

Having now described my invention, what I claim as new and desire to secure by Letters Patent, is:

1. A steam turbine comprising a plurality of stages or rows of blades with connecting steam passages so arranged that at reduced power all of the steam flows in series through 25 all of the stages or rows of blades, and at high power the steam flows through a portion of the stages or rows of blades, then subdivides and flows in parallel through some or all of the remaining stages or rows 50 of blades.

2. A steam turbine comprising a plurality of stages or rows of blades arranged in two or more separate chambers, there being connecting steam passages so arranged that at 25 reduced power all of the steam flows in series through all of the stages or rows of blades, and at high power the steam flows through a portion of the stages or rows of blades, then subdivides and flows in parallel 40 through some of all or the remaining stages or rows of blades.

3. A steam turbine comprising high pressure stages or rows of blades and low pressure stages or rows of blades with connecting steam passages so arranged that at reduced power all of the steam flows in series through all of the stages or rows of blades and at high power the steam flows through the first stage or rows of blades then subdivides and flows through the remaining high pressure stages or rows of blades in parallel with some or all of the low pressure stages or rows of blades.

4. A steam turbine comprising a high pressure element provided with stages or rows of blades and a low pressure element provided with stages or rows of blades in combination with an additional turbine element, connecting steam passages so arranged that at reduced power the steam flows in series through all the stages or rows of blades of the high pressure element then through the other elements to the exhaust, and at high power the steam flows through 65 a portion of the stages or rows of blades of

the high pressure element then subdivides and flows through the remaining stages or rows of blades of this element in parallel with some or all of the stages or rows of blades of the low pressure element and then 70 through the additional turbine element to the exhaust.

5. A steam turbine comprising a high pressure element provided with stages or rows of blades and a low pressure element provided 75 with stages or rows of blades in combination with additional turbine elements, connecting steam passages so arranged that at reduced power the steam flows in series through all the stages or rows of blades of 80 the high pressure element then through the additional turbine elements and at high power the steam flows through the first stages or rows of blades of the high pressure element then subdivides and flows 85 through the remaining high pressure stages or rows of blades of this element in parallel with some or all of the stages or rows of blades of the low pressure element and then through the additional turbines. 90

6. The combination with a high speed high pressure steam turbine element and a high speed low pressure steam turbine element, both connected to drive a propeller, and a low speed high pressure steam turbine element connected to drive a propeller, means for admitting steam into the inlet of the high speed high pressure steam turbine element, means for passing the steam from the outlet of the high speed high pressure steam turbine element to the inlet of the high speed low pressure steam turbine element, means for passing steam from the outlet of the high speed low pressure steam turbine element to the inlet of the low speed 100 high pressure steam turbine element, whereby the steam will flow in series through the high speed high pressure steam turbine element and the high speed low pressure steam turbine for reduced power, means for passing steam from the outlet of the high speed high pressure steam turbine element to the inlet end of the low speed high pressure steam turbine element, and means for passing steam from the inlet end of the high speed high pressure steam turbine element to the inlet end of the high speed low pressure steam turbine element so the steam will flow in parallel through the two high speed steam turbine elements to the low 110 speed steam turbine element for full power. 115

7. The combination with a high speed high pressure steam turbine element and a high speed low pressure steam turbine, both connected to drive a propeller, a low speed low pressure steam turbine element connected to drive the same propeller, and a low speed high pressure steam turbine element connected to drive a second propeller, means for admitting steam into the inlet 120 125 130

- end of the high speed high pressure steam turbine element, means for passing steam from the outlet of the high speed high pressure steam turbine element to the inlet end 5 of the high speed low pressure steam turbine element, means for passing steam from the outlet of the high speed low pressure steam turbine element to the inlet of the low speed high pressure steam turbine element, means 10 for passing steam from the outlet of the low speed high pressure steam turbine element to the inlet of the low speed low pressure steam turbine element, whereby the steam will flow in series through the four turbine elements 15 for reduced power, means for passing steam from the outlet of the high speed high pressure steam turbine element to the inlet of the low speed high pressure steam turbine element, means for passing steam from the inlet end 20 of the high speed high pressure steam turbine element to the inlet of the high speed low pressure steam turbine element so the steam will flow in parallel through the two high speed turbine elements 25 and in series through the two low speed steam turbines for full power.
8. The combination with a high speed high pressure steam turbine and a high speed low pressure steam turbine element, separate shafts for the two turbine elements, a propeller shaft, speed reducing mechanism connecting the shafts, a low speed high pressure steam turbine element, a propeller shaft connected thereto, means for admitting 30 steam into the inlet of the high speed high pressure steam turbine element, means for passing steam from the outlet of the high speed high pressure steam turbine to the inlet of the high speed low pressure steam 35 turbine element, means for passing steam from the outlet of the high speed low pressure steam turbine element to the inlet of the low speed high pressure steam turbine element, whereby the steam will flow in series through the high speed high pressure steam turbine element and the high speed low pressure steam turbine element for reduced power, means for passing steam from the outlet of the high speed high pressure 40 steam turbine element to the inlet of the low speed high pressure steam turbine element, and means for passing steam from the inlet end of the high speed high pressure steam turbine element to the inlet end of the high speed low pressure steam turbine element so that the steam will flow in parallel through the two high speed steam turbines to the low speed steam turbine elements for full power.
- 60 9. The combination with a high speed high pressure steam turbine and a high speed low pressure steam turbine element, a shaft for each turbine element, a propeller shaft, speed reducing mechanism connecting the shafts, a low speed low pressure steam 65 turbine element connected to the propeller shaft, a low speed high pressure steam turbine element, a second propeller shaft connected to the said low speed high pressure steam turbine element, means for admitting steam into the inlet end of the high speed high pressure steam turbine element, means for passing steam from the outlet of the high speed high pressure steam turbine to the inlet end of the high speed low pressure steam turbine element, means for passing steam from the outlet of the high speed low pressure steam turbine element to the inlet of the low speed high pressure steam turbine element, means for passing steam from the outlet of the low speed high pressure steam turbine element to the inlet of the low speed low pressure steam turbine element, whereby the steam will flow in series through the four turbine elements for reduced power, means for passing steam from the outlet of the high speed high pressure steam turbine element to the inlet of the low speed high pressure steam turbine element, means for passing steam from the outlet of the high speed high pressure steam turbine element to the inlet of the low speed high pressure steam turbine element, and means for passing steam from the inlet end of the high speed high pressure steam turbine element to the inlet of the high speed low pressure steam turbine element so the steam will flow in parallel through the two high speed turbine elements and in series through the two low speed turbine elements for full power.
10. A steam-turbine comprising a multistage high pressure steam turbine element, and a multistage low pressure steam turbine element, a shaft for each element, a propeller shaft, speed reducing mechanism connecting the shafts, means for admitting steam to the high pressure element, and means for passing steam from the outlet of the high pressure element to the inlet of the low element, whereby steam will flow in series through both elements for reduced power, means for admitting steam from an intermediate portion of the high pressure element to the inlet end of the low pressure element, and means for exhausting steam from the outlet of the high pressure element, whereby the steam will flow in parallel through the remaining stages or rows of blades of the high pressure element and some or all of the stages of the low pressure element for full power.
11. A steam-turbine comprising a multistage high pressure element, and a multistage low pressure element, a shaft for each element, a propeller shaft, speed reduction gearing connecting the shafts, in combination with an additional turbine element, means for admitting steam to the high pressure element, and means for passing steam from the outlet of the high pressure element to the inlet of the low pressure element, whereby at reduced power the steam will flow in series through both of the elements,

then through the additional element to the exhaust, means for admitting steam from an intermediate portion of the high pressure element to the inlet of the low pressure element, and means for exhausting steam from the outlet of the high pressure element whereby at full power the steam will flow through the first stage or rows of blades of the high pressure element, then subdivide 10 and flow through the remaining stages or rows of blades of this element in parallel

with some or all of the stages or rows of blades of the low pressure element and then through the additional element to the exhaust.

This specification signed and witnessed this twenty-third day of June, 1915.
